DESIGN FOR A WHEEL

J Harold Hunt, Lansing, Mich., assignor to Motor
Wheel Corporation, Lansing, Mich., a corpora-
tion of Michigan

Application October 11, 1933, Serial No. 49,452

Term of patent 7 years

To all whom it may concern:

Be it known that I, J Harold Hunt, a citizen of the United States, residing at Lansing, county of Ingham, State of Michigan, have invented a new, original, and ornamental Design for a Wheel, of which the following is a specification, reference being had to the accompanying drawing, forming a part thereof.

In the drawing:

Figure I is a side view of a wheel showing my new design;

Figure II is a perspective view of the wheel body shown in Figure I;

Figure III is an enlarged sectional view of a spoke taken on substantially the line III—III of Figure I; and

Figure IV is a profile view of the wheel shown in Figure I, taken on substantially the line IV—IV of that figure.

The essential features of the present design

consist of the form of the spokes and annular central portion of the wheel body and their proportion with respect to each other. The spokes are relatively short and of semi-cylindrical form. They flare axially outward at their inner extremities where they merge with the axially extending radially curved annular central portion. Thus the entire face of the wheel body is made up of convex surfaces when viewed from the front side thereof. The axial depth of the wheel body in the region of the annular central portion is substantially equal to the radial extent of the wheel body measuring from the annular central portion to the outer extremities of the spokes.

I claim:

The ornamental design for a wheel as shown and described.

In testimony whereof he has affixed his signature.

J HAROLD HUNT.
